FUEL PUMP

Sumner Wiltse, Dearborn, Mich.

Application January 25, 1932, Serial No. 588,736

12 Claims. (Cl. 103—152)

This invention relates to pumps of the diaphragm type and particularly to pumps especially designed for use as a fuel pump for an internal combustion engine.

In view of the present day tendency in the automotive industry towards higher and higher speeds and the desire to obtain very rapid acceleration, it has been found that the vacuum tanks heretofore most commonly employed for drawing the fuel from the gas tank and delivering it to the carburetor are in many cases not quite equal to the requirements of high speed quick acceleration operation and, therefore, the trend in the industry today is more and more towards the use of fuel pumps to replace the vacuum tanks. Such fuel pumps as have to date been adapted, at least as far as I am aware, depend upon actuating the pump from a cam shaft incorporated in the construction of the engine. While the camactuated fuel pump operates fairly successfully, it too, is subject to some objections, among which may be noted the difficulty in causing the pump to function unless it is primed and the length of time required to cause the pump to become primed at such times as the gasoline supply in the gas tank and carburetor has been completely exhausted. Another most serious objection to the camshaft operated fuel pump is due to the rapid reciprocation of such pump at high speeds with consequent high fluid friction, hence, high temperature and vaporization of the fuel, and the resultant production of vapor locks in the fuel line with a consequent failure of the pump to function and deliver the required quantity of fuel.

The principal object of the present invention is to produce a new and improved construction in a fuel pump for internal combustion engines in which the objections inherent to vacuum tanks and camshaft operated fuel pumps will be obviated.

Another object of the invention is to provide a new and improved construction for a fuel pump in which the pumping action is relatively slow and of such a nature that practically no appreciable fluid friction is developed and the formation of vapor locks is prevented.

A further object is to provide a fuel pump which will deliver the fuel at a pre-determined uniform pressure as required by the engine and carburetor.

Another object is to provide a pump in which the suction stroke thereof is caused to be effected by the creation of a vacuum on one side of a flexible diaphragm and the discharge stroke is ef-

fected by the pressure of a spring which is so designed as to insure a practically constant pressure of the fuel throughout the entire discharge stroke.

A further object is to provide a pump of the character described in which the vacuum for effecting the suction stroke of the diaphragm is furnished by two or three different sources which are automatically made effective as determined by operating conditions.

Another object is to provide a pump of the character described in which the suction stroke is automatically effected either by suction in the intake manifold, suction from the intake of the oil pump or suction produced by a plunger actuated by a cam incorporated in the engine structure but which is not normally in operation when the suction from either of the two first mentioned sources is sufficient to effectively operate the pump.

A further object is to provide a pump of the character described in which a shaft is secured to, and in axial alignment with, the pump diaphragm reciprocates with said diaphragm and its reciprocation is employed to actuate a valve automatically at the ends of the stroke of the diaphragm to place the under side of the diaphragm alternately in communication with the source of suction or with atmospheric pressure.

Another object is to provide a construction in which the full stroke of the diaphragm of the pump will be insured on each reciprocation thereof.

A further object is to provide a pump in which there is a minimum clearance and another object is to provide a device of simple construction that can readily be employed for manual priming of the pump, should such priming become necessary.

The above and further objects of the invention will be apparent to those skilled in the art from the following more detailed description and by reference to the accompanying drawings wherein I have shown, by way of illustration, a satisfactory constructional example of a fuel pump embodying the principles of my invention that has operated highly successfully in actual commercial operation.

In the drawings, Fig. 1 is a central vertical section through a fuel pump constructed in accordance with the invention, a part thereof being shown in elevation; Fig. 2 is an enlarged view of the central shaft of the pump with the valve and valve actuating means operated thereby; Fig. 3 is an enlarged sectional detail on the line 3—3 55

of Fig. 1; Fig. 4 is a section on the line 4—4 of Fig. 2; Fig. 5 is an enlarged detail showing the hand priming device in position for the priming operation; Fig. 6 is a side elevation, partly in section, and showing the cam operated cylinder and plunger for producing suction, and Fig. 7 is a plan view of the bottom closure member for the pump casing shown in Fig. 6.

As most clearly shown in Fig. 1 of the drawings, the pump includes a casing formed by a lower member 10 and an upper member 11, each of said members being provided with lateral flanges with which any suitable fastening means, such as the screws 12, are engaged for securing the casing members together in assembled condition. Clamped between the flanges of the casing members is a pump diaphragm 13, which may be of any suitable construction. The upper casing member 11 is provided with a lateral extension or boss 14, provided with a conduit 15 that communicates with the pump chamber 16, formed as clearly shown, by the casing members 10 and 11 in assembled condition and in which chamber 16 the diaphragm 13 is located. The lateral extension 14 of the casing member 11, is provided with an annular seat 16a surrounded by a periphery flange 17 for the reception of a settling chamber or sump 18 through which the fuel passes in its travel from the gas tank to the fuel pump. The chamber 18, in accordance with the usual construction of devices of this character, is preferably constructed of glass and is held in position against its seat by means of a bail 19 which is pivotally connected at its upper end to the extension 14 and carries at its lower end a knurled threaded nut 20 adapted to engage the rounded protuberance 21 of the chamber 18 so as to clamp the said chamber in fluid tight engagement with the seat 16a, a sealing gasket or washer 22, preferably being interposed between said chamber 18 and the seat 16a.

The lateral extension 14 also includes a conduit 23, which at one end terminates in a pipe threaded counter bore in which may be screwed the end of a pipe which communicates with the gas tank. The other end of the conduit 23 terminates in a downwardly extending nozzle portion 24 which communicates with the interior of the chamber 18. A sediment collecting screen 25 is seated within a small annular recess provided in the upper face of the chamber 18 and has a central aperture adapted to fit snugly over the reduced lower end of the nozzle 24. Communication between the interior of the chamber 18 and the conduit 15 is established through a small lateral extension 26 of the conduit 15 under the control of a valve 27 which may be of any suitable construction but which is shown as a ball valve of the common construction which seats upon a small annular valve seat provided at the upper end of the conduit extension 26. Access to the valve 27 is readily secured by removing a threaded plug 28 screwed into a boss 29 projecting from the lateral extension 14 and immediately above the seat for said valve.

The upper casing member 11 is provided, substantially in axial alignment with the pump chamber 16, with an upwardly extending hollow screw threaded boss 29a to which may be secured a pipe leading to the carburetor and communication between the pump chamber 16 and the carburetor is established under the control of a ball valve 30 adapted normally to seat upon an annular valve seat provided at the lower end of the boss 29a for its engagement. The ball valve 30

is preferably held upon its seat by means of a small coil spring 31 which abuts a plug 32 screw threaded into the boss 29.

The lower casing member 10 is provided, immediately below the pump chamber 16, with an annular flange 33 which defines a cylindrical chamber 34 for the reception of a coil spring 35 and the bottom of said cylindrical chamber is closed, except as presently to be described, by a continuation 36 of the flange 33. The continuation 36 of the flange 33 merges into and is integral with a bearing boss 37, the bore of which is substantially in axial alignment with the pump chamber 16. Mounted for reciprocation within the bearing boss 37, is a central diaphragm shaft 38 which at its upper end is reduced and screw threaded to pass through a suitable aperture provided at the center of the diaphragm 13. The diaphragm 13 is clamped in assembled relation with the shaft 38 by means of a pair of small cup-shaped disc washers 39, one located on each side of the diaphragm and by a nut 40 and small washer 41, the nut 40 being in threaded engagement with the screw threaded end of the shaft 38; a washer 42 is preferably interposed between the lower side of the diaphragm 13 and a shoulder of the shaft 38.

The lower end 38a of the shaft 38 is slidably engaged within a hollow boss or bearing 43, preferably formed integral with a bottom closure member or cap 44, secured to the lower flanged end of the casing member 10 by any suitable means such as the screws 45. Intermediate its ends the shaft 38 is reduced in diameter as indicated by the reference character 38b, to provide a pair of spaced shoulders 38c and 38d. Located between the shoulders 38c and 38d and straddling the reduced portion 38b of the shaft 38 are the arms 46a of the yoked end of an actuating lever 46. At its other end the lever 46 is pivotally connected by means of a pin 47 with a cooperating or combination valve actuating lever 48, the two valve actuating lever members 46 and 48 forming a composite jointed lever for the actuation of a valve 49 by the reciprocation of the shaft 38. This composite lever is supported by means of the pivot pin 47 in a bracket 50 which projects upwardly from the bottom closure cap 44 of the pump casing. The lever member 48 is provided with a pair of laterally extending arms 48a, each of which is notched adjacent to its outer extremity for the reception of one end of a coil spring 51. The other ends of the springs 51 are engaged with the similarly notched ends of a pin 52 which is secured within the downwardly extending flanged portion of the lever member 46. The member 46 is provided with a pair of laterally projecting stops 46b and 46c adapted to engage with the lower face of the flanged continuation member 36 of the lower casing 10 and the upper face of the closure cap 44 respectively. The lever member 48 is provided intermediate its ends with a notch or slot 48b in which is adapted to be engaged the reduced central part 49a of the valve member 49.

The upper end of the valve 49 terminates in a cone shaped valve seating surface 49b adapted to close an aperture 53 which leads to atmosphere and is provided in a small cup-shaped valve seat 54 while the lower end of the valve 49 is adapted to close a smaller aperture 55 provided in a similar valve seat 56. The aperture 55 communicates with a branched conduit 57 formed in the closure cap 44 and the ends of which conduit terminate in the upwardly extending lateral branches 58.

and 59. The conduit branches 58 and 59 terminate in and communicate with the valve chambers 60 and 61 respectively in which are seated the ball valves 62 and 63 respectively. The valve chambers 60 and 61 are located within the externally threaded bosses 64 and 65 which are adapted to be connected the coupling members 66, 67, which serve to connect to said bosses the ends of the pipe lines 68, 69 respectively. Secured 10 between the end of each pipe line and the boss to which it is connected, is a valve retaining plug 70, such as shown at the left hand side of Fig. 3.

The pipe line 68 is connected at its other end to any suitable source of suction, as for example, 15 the inlet side of the oil pump of the internal combustion engine to which the fuel pump is intended to deliver fuel while the other end of the pipe line 69 is in communication with another potential source of suction, such as the intake 20 manifold of said engine.

A pump constructed in accordance with the principles of the present invention may also include a third source of suction which, as shown most clearly in Figs. 6 and 7 of the drawings, 25 comprises a small cylindrical chamber 71, preferably formed within the lower pump casing member 10. Mounted for reciprocation within this cylinder 71 is a plunger 72 which at the inner end thereof has secured to it, in any suitable 30 way, a small cup-shaped washer 73 of the type commonly used in air pumps. The side flanges or walls of said washer are preferably urged into engagement with the walls of the cylinder 71 by means of a small coil spring 74. At its other 35 end the plunger 72 is provided with an enlarged head 75. Preferably seated within the outer face of the head 75 is a hardened wear plate 76 with which is adapted to engage a cam throw 77 of a small camshaft 78 provided within the crank-case of the internal combustion engine and 40 adapted to be driven from the crankshaft, or any other rotating part of the engine, by any suitable driving means, not shown. It will be noted that the cylinder 71 is located substantially centrally 45 of a flange 79 of the pump casing 10 and that said flange is adapted to be secured to the crank-case 80 of the engine and so that the cylinder 71 with the plunger 72 projects into the interior of 50 said crank-case. The plunger 72 is normally urged by means of a spring 81 outwardly of its cylinder 71 so as to cause the wear plate 76 to engage with the cam throw 77.

It will be noted upon inspection of Fig. 1 of the drawings that the valve member 49 with its composite actuating lever is located within a chamber 82 formed in the lower end of the casing member 10. Communication is established between the chamber 82 and the cylindrical portion 34 of the casing member 10 in which the spring 35 is mounted, through one or more apertures 83 formed in the lateral continuation 36 of the flange 33.

The lower end of the bearing boss 43 for the lower end of the shaft 38 is adapted to be closed by an internally threaded cup-shaped cap member 85, which, when the pump is in normal operating condition is screwed to said boss 43 in the manner shown in Fig. 1. For the purpose of enabling the pump to be readily primed by manual operation the cap 85 is provided with a small shaft like extension 86 which at its outer end is reduced and screw threaded as indicated at 87. The screw threaded end 87 of the cap is adapted to be engaged within a small screw threaded hole 88, provided in the lower end of the shaft 38.

When it is desired to prime the pump manually the cap is unscrewed and its threaded end 87 screwed into the hole 88 of the shaft 38 as shown in Fig. 5 of the drawings.

The manner in which the device operates is as follows:

Let it be assumed that the conduit 23 at the outer end of the lateral extension 14 of the upper casing member 11 is connected with the gas supply tank of an internal combustion engine by any suitable piping means and that the cap, or plug 32 at the upper end of the boss 29a of the casing 11 is similarly connected to the carburetor. If the entire fuel line and carburetor is empty the pump may be primed manually by connecting the cap 85 to the shaft 38 in the manner shown in Fig. 5, and reciprocating the shaft 38 by hand. Ordinarily however, manual priming of the pump will not be required because if the choke of the engine is pulled out and assuming that there is no gasoline in the carburetor, and the float valve thereof is open, sufficient suction will be produced in the fuel line leading from the fuel pump to the carburetor to cause the valves 30 and 21 to be raised from their seats and the suction through the carburetor will cause the fuel to be drawn directly from the gas tank through the pump above the diaphragm 13 without any reciprocation of the diaphragm being effected.

When the engine is operated the suction produced in the intake manifold, particularly when the engine is idling, at which time said suction is greatest, will be effective through the pipe 69 to the fuel pump and said suction will raise the valve 63 off its seat, the suction then being communicated through the conduit 58 and branch conduit 57 and the aperture 55 to the chamber 82 thence through the aperture 83 to the under side of the diaphragm 13. The spring 34 which normally urges the diaphragm 13 upwardly is of sufficient strength to deliver fuel from the pump chamber 16 to the carburetor, but is not strong enough to prevent the diaphragm 13 from being sucked downwardly by the suction communicated to the under side of the diaphragm from the intake manifold. I have found in actual practice that a vacuum of about 1½ pounds is sufficient to operate the pump. Assuming that the vacuum in the intake manifold is above this amount the diaphragm will be drawn downwardly to approximately its full limit of travel, as shown in Fig. 1 of the drawings. Shortly before the diaphragm reaches such limit the shoulder 38c of the shaft 38 will have engaged with the arms 46a of the composite valve actuating lever formed by the members 46, 48 and will cause said arms to move downwardly until the lever member 46 rotating on its pivot causes the springs 51 to be moved past center thereby to exert a downward pull on the lever member 48 that causes the valve 49 to be drawn to its lowermost position of travel and bring the valve seating surface 49c at the lower end of the valve member 49 into engagement with the valve seat 56, thus closing the aperture 55 and cutting off the underside of the diaphragm 13 from the source of suction. The movement of the valve 49 to its lowermost position causes the valve seating surface 49b at the upper end thereof to move out of engagement with the valve seat 54 thereby to establish communication between the underside of the diaphragm and the atmosphere. Fig. 1 of the drawings shows the parts when the condition just described has been established. The shutting off of the communication between the

source of suction and the underside of the diaphragm permits the spring 35 which has been compressed by the action just described, to begin to function. It will be assumed that the 5 downward movement of the diaphragm just described has drawn a charge of fuel through the conduit 23, nozzle 24, chamber 18 and conduits 26 and 15 into the pump chamber 16; the suction produced by the downward movement of the 10 diaphragm in the pump chamber 16 of course causes the ball valve 27 to be raised from its seat and the ball valve 30 to be drawn to its seat. As the spring 35 begins to function the diaphragm 13 will be moved slowly upwardly by the action 15 of the spring thereby causing the fluid within the pump chamber 16 to be ejected from said chamber past the valve 30, the pressure produced within the pump chamber causing the valve 30 to open and the valve 27 to close. If, during the 20 upward movement of the diaphragm, a sufficient amount of fuel has been delivered to the carburetor to cause the float of the carburetor to close the carburetor float valve and thereby produce a back pressure in the fluid being delivered 25 into the carburetor which results in a greater pressure being developed on the upper side of the diaphragm than the spring 35 is able to overcome, the upward movement of the diaphragm and the shaft 38 will cease until the carburetor 30 float valve is again permitted to open thereby reducing the back pressure in the delivery line of the fuel pump and permitting the diaphragm to resume its pressure stroke. As the diaphragm approaches its upper limit of travel, the shoulder 33d will engage with the arms 46a of the lever 46 and will move the same upwardly until the springs 51, having been moved past the pivotal center of the composite lever 46, 48, will cause the lever 48 to be snapped upwardly carrying 40 with it the valve 49 and bringing about the closure of the aperture 53 which leads to atmosphere and the opening of the aperture 55 which communicates with the branched conduit 57 connected to the sources of suction.

45 As the suction within the intake manifold is greatest during the idling stroke but is markedly reduced when the engine is operating at highest speeds, or under very heavy loads, the pump might not operate with its highest efficiency to deliver the requisite amount of fuel under all conditions if the suction in the intake manifold alone were relied upon to produce the suction required to bring about the suction stroke of the diaphragm 13. In order to provide for this contingency the fuel pump is also connected to a second source of suction, namely, the intake side of the oil pump of the engine, this connection being made through the pipe 68. As above pointed out, the suction in intake manifold is reduced at 50 high speeds, but as the speed of the oil pump increases proportionately with the speed and rotation of the engine, the suction at the intake side of the oil pump will, therefore, be increased when the engine is operated at high speed and consequently at a high speed engine operation the suction within the pipe line 68 will be higher than that within the pipe line 69. When these conditions arise the ball valve 62 will be raised from its seat while the ball valve 63 will be closed 55 and the suction produced on the under side of the diaphragm will then be that of the suction produced in the pipe line 68. Of course, when the engine is operated at low speed with comparatively small loads, the suction on the intake side of the oil pump will not be as great as that

within the pipe line 69 and the ball valve 62 will be closed while the ball valve 63 will be opened.

While it has been found that for ordinary conditions the provision of the two sources of suction just described namely, intake manifold suction 5 and suction from the intake side of the oil pump will be sufficient for insuring the efficient operation of the fuel pump, I may provide a third source of suction which will be brought into operation automatically should either of the two 10 sources of suction just mentioned be insufficient to insure the pump's operation. This third means of suction is shown most clearly in Fig. 6 of the drawings and comprises the cylinder 71 and plunger 72. The spring 81 which normally tends 15 to urge the plunger 72 into engagement with the cam throw 71, is designed to move the plunger 72 outwardly of its cylinder whenever the suction within the branch conduit 57, chamber 82 and diaphragm 13 drops below the requisite amount 20 necessary to pull the diaphragm downwardly against the action of the spring 35. Whenever this condition arises, the spring 81 will move the plunger 72 outwardly until it is engaged by the cam throw 71. When the plunger is engaged with 25 the cam throw 71, it will be caused to be reciprocated within its cylinder 71. On the inward stroke of the plunger any air contained within the cylinder 71 will flow past the cup-shaped washer 73 and through the conduit 72a and aperture 72b to atmosphere, while on the outward stroke of the plunger the sides of the cup-shaped washer will be drawn into close fitting engagement with the inner walls of the cylinder and suction will be produced within the inner end of 30 the cylinder thereby raising the ball valve 91 off its seat and producing suction in conduit 90 and chamber 82 and below the diaphragm 13.

As will be seen from the foregoing a fuel pump constructed in accordance with the present invention will be operated primarily in combination with an internal combustion engine by suction induced in the intake manifold of the engine and communicated to the underside of the diaphragm of the pump and that automatically, in accordance with operating conditions of the engine, such suction may be developed below the pump diaphragm by the suction induced in the intake side of the oil pump; that the invention also contemplates the possible, but not essential, use of 45 a third source of suction developed by what may be termed an additional mechanically operated accessory driven by a rotating part of the engine and which accessory includes a plunger or piston reciprocating in a suitable cylinder.

As hereinbefore pointed out the fuel pump is so constructed that it will be primed directly by the suction produced in the intake manifold when the choke valve of the intake airline for the fuel mixture is closed. As a result a pump constructed 50 in accordance with the invention may be primed much more quickly than is the case with fuel pumps of the type now commonly used in which the reciprocation of the pumping media is effected entirely by mechanical means driven by 55 a rotating part of the engine. The pump of the present invention also includes a convenient hand priming means.

As will be readily understood from the foregoing description and the accompanying drawings, 70 the fuel pump herein disclosed will operate at a relatively slow speed because, as will be seen, the diaphragm 13 will always travel through its full stroke due to the fact that reversal of the diaphragm is effected by the alternate establishing of 75

communication between its underside with one of the sources of suction and the atmosphere, and this alternate establishment of communication is effected by the operation of the valve 49, which 5 in turn is only caused to be moved from one position to another when the diaphragm in its movement, either upwardly or downwardly, reaches its limit of travel. The fuel pump, therefore, is a pump of constant stroke and fixed displacement. Its speed of operation will depend entirely upon the requirements of the engine for fuel. For example, if it be assumed that the diaphragm 10 is traveling upwardly and delivering fuel through the pipe line that leads to the carburetor and a sufficient quantity of fuel has been fed to the carburetor such as to cause the float valve thereof 15 to be closed, the back pressure in the delivery or outlet line of the fuel pump produced by the closing of the carburetor float valve will be sufficient 20 to stop the upward travel of the diaphragm and this travel will not again be resumed until the float valve of the carburetor is again opened after which the diaphragm will continue its upward travel until its full stroke has been completed 25 and the valve 49 operated to again place the underside of the diaphragm in communication with one of the sources of suction. It will be understood that there may be any number of interruptions or pauses in the upward travel of 30 the diaphragm but that its downward stroke will proceed uninterruptedly after the underside of the diaphragm is placed in communication with the source of suction. From what has just been 35 stated it will also be seen that the pump is a variable speed pump but of constant stroke and fixed displacement.

While I have shown by way of illustration an embodiment of the invention that has worked highly satisfactorily in actual operation, it will 40 be understood that the invention is not limited to the specific constructional details shown and described. For example, the use of check valves in certain of the conduits is not absolutely essential, nor is the use of a sump in the line between 45 the pump and the gas tank. Likewise, the use of the third or mechanical operated source of suction is not essential. It will thus be understood that many changes, variations and modifications may be resorted to without departing 50 from the spirit of the invention.

I claim:

1. In a fuel pump for use in conjunction with an internal combustion engine, housing means, pumping means including a chamber and a flexible diaphragm dividing said chamber into a fuel pumping compartment and a suction receiving compartment, each of which compartments occupy in alternation a common volumetric space, said fuel pumping compartment having a fuel inlet and outlet, resilient means in engagement with said diaphragm and normally urging it with a predetermined maximum yielding pressure to perform a pumping stroke, a reciprocating guide shaft secured to said diaphragm in axial alignment therewith for preventing objectionable distortion of said diaphragm, a pair of spaced valve seats having ports for alternately establishing communication between said motor chamber and sources of vacuum and atmosphere, a valve 60 freely mounted for frictionless movement between said pair of valve seats and provided with valve seating surfaces for engagement with said seats, and lost motion connections between said valve and guide shaft to cause said valve to be actuated into engagement with said seats in al-

ternation as said diaphragm reaches the ends of said working chamber, said connections including a lever extending between said valve and shaft and spring means coacting with said lever normally to hold said valve in engagement with one or the other of said valve seats. 5

2. In a fuel pump for use in conjunction with an internal combustion engine, housing means, pumping means including a chamber therein, motor means for driving the pumping means, a flexible diaphragm mounted within said chamber and separating the pumping chamber from the motor means, said diaphragm constituting a part of the pumping means, a suction receiving compartment connected to the motor means, a guide shaft connected to the central part of said diaphragm insuring rectilinear reciprocation of said central part, resilient means for normally urging said diaphragm in a direction to perform a pumping stroke, means for alternately connecting said suction receiving compartment to a source of suction induced by the operation of the engine and to atmosphere, including a pair of spaced valve seats, a valve freely mounted for movement between said seats and having a pair of valve seating surfaces for engagement with said seat, a freely mounted jointed two-part lever extending between and loosely supported by said guide shaft and valve and over-center spring means for causing said lever normally to hold one or the other of the valve seating surfaces of said valve in engagement with one or the other of said valve seats. 20 25 30

3. In a fuel pump for use in conjunction with an internal combustion engine, a housing assembly having a pump chamber and pumping means therein, motor means for the pumping means also within the housing assembly, a cover plate detachably secured to said housing assembly and defining therewith a valve chamber communicating with the motor means, said cover plate being provided with a main conduit communicating with said valve chamber and a plurality of sources of suction induced by the operation of said engine, means for closing communication between certain of said sources of suction and said chamber, a valve operated by said motor means and controlling communication between said main conduit and valve chamber, and means for establishing communication between said valve chamber and another of said sources of suction upon one becoming inoperative. 40 45 50

4. In a fuel pump for use in conjunction with an internal combustion engine, said pump comprising housing means defining a working chamber, a flexible diaphragm mounted for reciprocation within said chamber and dividing it into a fuel pumping compartment and a suction receiving compartment, a guide shaft connected to the central part of said diaphragm, a bearing for said shaft, a cover plate detachably secured to said housing and defining therewith a motor chamber, a pair of apertured valve seats for alternately establishing communication between said suction receiving compartment and sources of suction induced by the operation of said engine and with the atmosphere, a valve freely mounted in said motor chamber for movement between said valve seats to establish and interrupt in alternation communication between said sources of suction and the atmosphere, a freely mounted toggle lever extending between said valve and said guide shaft and having lost motion connections with the latter to cause said valve to be actuated only at the ends of the stroke of said dia- 55 60 65 70 75

phragm and resilient means connected to said lever to cause it to hold said valve normally in engagement with one or the other of said valve seats.

5. In a fuel pump for use in conjunction with an internal combustion engine, a casing structure, a pumping chamber portion and pumping means therein, motor means for controllingly driving said pumping means, including a valve chamber, a portion also within said casing structure and located below said pumping chamber and provided with valved inlets for furnishing communication between sources of suction and atmosphere, a suction inlet being in the lowermost 10 wall of said valve chamber portion whereby any water of condensation formed within said valve chamber will gravitate towards said suction inlet to be carried off by said suction thereby to prevent accumulation of said water within said 15 pump.

6. An operating motor for a fuel pump particularly adapted for use with an internal combustion engine, said pump having a housing defining a working chamber, a flexible diaphragm mounted 20 for reciprocation within said chamber and dividing it into a fuel pumping compartment and a motor compartment, a guide shaft connected to the central part of said diaphragm, a bearing for said shaft located in axial alignment with the 25 center of said diaphragm and the motor chamber, said shaft projecting into the motor chamber, a cover plate for said motor chamber having a bearing for said shaft, a pair of spaced shoulder portions carried by a central part of said shaft, 30 a pair of apertured valve seats for alternately establishing communication between the motor chamber and atmosphere and between said chamber and sources of suction induced by the operation of said engine, a valve freely mounted in 35 said valve chamber for movement between said valve seats to make and break such communication, a freely mounted toggle lever extending between said valve and said guide shaft and comprising a pair of yoked end lever arms pivotally 40 connected adjacent the center of said toggle lever, the yoked end of one of said lever arms spanning the central part of said shaft to be engaged by said shoulder portions and said valve having spaced shouldered actuating portions and an intermediate part spanned by the yoked end of the 45 other of said levers, and over-center spring means connected to said lever arms and crossing the center of said toggle lever to cause it to hold said valve normally in engagement with one or the 50 other of said valve seats.

7. An operating motor for a fuel pump particularly adapted for use with an internal combustion engine, said pump having a pumping diaphragm, yielding means for causing it to effect a pumping stroke at a substantially constant pressure, a guide shaft connected to said diaphragm, a freely mounted frictionless valve for establishing communication between the underside of said diaphragm alternately with a source of suction 60 and the atmosphere, a frictionless freely mounted lever between said valve and guide shaft and having lost motion connection with said shaft, and means for connecting said valve automatically with a source of suction caused by a piston and cylinder mechanically operated from a rotating part associated with the engine.

8. An operating motor for a fuel pump particularly adapted for use with an internal combustion engine, said pump having a pumping diaphragm, yielding means for causing it to effect a

pumping stroke at a substantially constant pressure, a guide shaft connected to said diaphragm, a freely mounted frictionless valve for establishing communication between the underside of said diaphragm alternately with sources of suction 5 and the atmosphere, a frictionless freely mounted lever between said valve and guide shaft and having lost motion connection with said shaft, and means for connecting said valve automatically with sources of suction, said sources of suction being the intake manifold of the engine, the intake side of the engine's oil pump and a piston and cylinder mechanically operated by a rotating part associated with the engine.

9. An operating motor for a fuel pump particularly adapted for use with an internal combustion engine, said pump having a pumping diaphragm, yielding means for causing it to effect a pumping stroke at a substantially constant pressure, a guide shaft connected to said diaphragm, a 15 freely mounted frictionless valve for establishing communication between the underside of said diaphragm alternately with sources of suction and the atmosphere, a frictionless freely mounted lever between said valve and guide shaft and having lost motion connection with said shaft, and means for connecting said valve automatically with sources of suction, said sources of suction being the intake manifold of the engine, the intake side of the engine's oil pump and a piston and cylinder mechanically operated by a rotating part associated with the engine, and means for operating said piston and cylinder only when said other sources of suction are inadequate.

10. An operating motor for a fuel pump particularly adapted for use with an internal combustion engine, said pump having a housing defining a working chamber, a flexible diaphragm mounted for reciprocation within said chamber and dividing it into a fuel pumping compartment and a suction receiving compartment, each of which compartments occupy in alternation a common volumetric space, a valve chamber characterized by a guide shaft connected to the central part of said diaphragm, a bearing for said shaft located in axial alignment with the center of said diaphragm and the valve chamber below said bearing into which said shaft projects, a cover plate for said valve chamber having a bearing for said shaft, said shaft having its central 30 portion reduced between said bearing to provide a pair of spaced shoulders, a pair of apertured valve seats for establishing communication between sources of suction induced by the operation of said engine with the atmosphere, a valve 35 freely mounted in said valve chamber for movement between said valve seats to establish and interrupt in alternation communication between said sources of suction and the atmosphere, a freely mounted toggle lever extending between 40 said valve and said guide shaft and comprising a pair of yoked end lever arms pivotally connected adjacent the center of said toggle lever, the yoked end of one of said lever arms spanning the reduced central portion of said shaft to be engaged 45 by said shoulders, and said valve having a reduced central portion spanned by the yoked end of the other of said levers, and resilient means connected to said lever arms and crossing the center of said toggle lever to cause it to hold said 50 valve normally in engagement with one or the other of said valve seats.

11. An operating motor for a fuel pump of the type particularly adapted for use with an internal combustion engine and having a housing de- 75

fining a working chamber with a flexible diaphragm mounted for reciprocation within said chamber and dividing it into a fuel pumping compartment and a motor compartment, said housing having a central bearing located in axial alignment with said diaphragm and an annular space between said bearing and the outer walls of said housing, and said housing being further provided with an open recess below said working chamber, a cover plate detachably secured to said housing and defining with said recess a valve and valve operating mechanism chamber, said cover plate being provided with a bearing in axial alignment with said first named bearing, a guide shaft secured to the center of said diaphragm and supported in said bearings, said shaft having its central portion reduced between said bearings to provide a pair of spaced shoulders, a pair of axially aligned apertured spaced valve seats, one in said housing and the other in said cover plate, one of said valve seats providing communication between said valve chamber and atmosphere, a conduit connecting the other of said valve seats with a source of suction induced by the operation of said engine, a valve freely mounted in said valve chamber for movement be-

tween said valve seats to establish and interrupt in alternation communication between said source of suction and the atmosphere, a freely mounted toggle lever extending between said valve and said guide shaft and comprising a pair of yoked end lever arms pivotally connected adjacent the center of said toggle lever, the yoked end of one of said lever arms spanning the reduced central portion of said shaft to be engaged by said shoulders, and said valve having a reduced central portion spanned by the yoked end of the other of said lever arms, and resilient means connected to said lever arms and crossing the center of said toggle lever to cause it to hold said valve normally in engagement with one or the other of said valve seats. 15

12. An operating motor as set forth in claim 11 in which said cover plate is provided with a plurality of conduits each leading to different sources of suction produced by the operation of the engine and each of said conduits having interposed therein valve means for automatically establishing communication between said valve chamber and that source of suction which at any instant is strongest. 20
